ATTYS.

UNITED STATES PATENT OFFICE.

JAMES CHRISTY, OF AKRON, OHIO.

DESIGN FOR AN AUTOMOBILE-TIRE.

44,235.

Specification for Design.

Patented June 24, 1913.

Application filed May 24, 1912. Serial No. 699,566. Term of patent 14 years.

To all whom it may concern:

Be it known that I, JAMES CHRISTY, a citizen of the United States, residing at Akron, county of Summit, and State of Ohio, have invented a new, original, and ornamental Design for an Automobile-Tire, of which the following is a specification, reference being had to the accompanying drawing, forming part thereof.

Figure 1 is a plan view of a portion of a

tire, and Fig. 2 is a side view thereof, showing my new and ornamental design.

I claim:

The ornamental design for an automobile tire, as shown.

JAMES CHRISTY.

Witnesses:

E. M. FISHER,
H. T. FISHER.
